UNITED STATES PATENT OFFICE.

CHARLES HOWARD MERWARTH, OF SOUTH BETHLEHEM, PENNSYLVANIA.

DESIGN FOR A GASKET OR PACKING FOR JOINTS OF PIPE OR OTHER APPARATUS.

SPECIFICATION forming part of Design No. 32,695, dated May 22, 1900.

Application filed April 23, 1900. Serial No. 14,044. Term of patent 14 years.

To all whom it may concern:

Be it known that I, CHARLES HOWARD MERWARTH, of South Bethlehem, in the county of Northampton, and in the State of Pennsylvania, have invented a certain new and original Design for a Gasket or Packing for the Joints of Pipes or other Apparatus; and I do hereby declare that the following is a full, clear, and exact description thereof, reference being had to the accompanying drawings, in which—

Figure 1 is a plan view of a gasket or packing, showing my new design; and Fig. 2 is a cross-section of the same.

Letters of like name and kind refer to like parts in each of the figures.

The object of my invention is to provide a design for gaskets or packing for the joints of pipes or other apparatus; and to this end said invention consists in the design for a

gasket or packing, substantially as herein shown and described.

The leading feature of my design consists in the shape or configuration, which comprises an inner ring A and outer ring B and spiral coils of wire C and C. The latter are attached by their outer ends to the outer periphery of the outer ring B.

Having thus described my invention, what I claim is—

The design for a gasket or packing for the joints of pipe or other apparatus, substantially as herein shown and described.

In testimony that I claim the foregoing I have hereunto set my hand this 7th day of April, 1900.

CHARLES HOWARD MERWARTH.
